US0D1094320S

(12) **United States Design Patent** (10) **Patent No.:** **US D1,094,320 S**
(45) **Date of Patent:** **** Sep. 23, 2025**

(54) **SUSCEPTOR**

(71) Applicant: **NuFlare Technology, Inc.**, Kanagawa (JP)

(72) Inventors: **Kunihiko Suzuki**, Shizuoka (JP); **Takuto Umetsu**, Kamakura (JP)

(73) Assignee: **NuFlare Technology, Inc.**, Kanagawa (JP)

(**) Term: **15 Years**

(21) Appl. No.: **29/888,118**

(22) Filed: **Mar. 28, 2023**

(30) **Foreign Application Priority Data**

Oct. 20, 2022 (JP) ..... 2022-022678 D

(51) **LOC (15) Cl.** **13-03**

(52) **U.S. Cl.**

USPC **D13/182**

(58) **Field of Classification Search**

USPC D13/182, 147, 133, 162, 199; D14/433, D14/435, 435.1

CPC H01L 21/68735; H01L 21/68785; C23C 16/4585; C30B 25/12

See application file for complete search history.

(57) **CLAIM**

The ornamental design for a suscepter as shown and described.

DESCRIPTION

FIG. 1 is a perspective view of a suscepter showing our new design

FIG. 2 is a front elevational view thereof,

FIG. 3 is a rear elevational view thereof,

FIG. 4 is a left side elevational view thereof,

FIG. 5 is a right side elevational view thereof,

FIG. 6 is a top plan view thereof,

FIG. 7 is a bottom plan view thereof; and,

FIG. 8 is an enlarged partial cross-sectional view taken along line 8-8 in FIG. 2.

1 Claim, 7 Drawing Sheets
